UNITED STATES PATENT OFFICE.

CHARLES ZABEL, OF CORAOPOLIS, PENNSYLVANIA, ASSIGNOR TO McDOWELL MANUFACTURING COMPANY, OF MILLVALE, PENNSYLVANIA, A CORPORATION OF PENNSYLVANIA.

MECHANICAL RACING TOY.

Application filed June 29, 1925. Serial No. 40,145.

This invention is for an improvement in mechanical toys of the type in which one or more objects are propelled by gravity around a gyrating track in simulation of a race.

5 The invention relates to toys of the general type disclosed in my co-pending application for patent Serial No. 665,114, filed September 27, 1923.

In toys of this type, a gyratory motion is 10 imparted to a suitable pan having one or more continuous tracks thereon. As the pan gyrates, gravity propelled objects, guided by the tracks, are caused to travel thereabout continuously in one direction. Where there 15 are two or more tracks, the appearance of a race is simulated and an extremely attractive and fascination toy is provided.

The present invention has for its principal object to provide a novel and simple 20 mechanism for tilting the pan to give it the proper gyratory motion.

The invention which may be varied in 25 various ways, may be understood by reference to the accompanying drawings in which three forms are shown. In the drawings:

Figure 1 is a top plan view of an assembled toy.

Figure 2 is a transverse section through one form of the toy.

30 Figure 3 is a similar view of a modified form.

Figure 4 is a plan view of a form of cross frame employed in the constructions of Figs. 2 and 3 and to which the pan is secured.

35 Figure 5 is a view similar to Fig. 3 showing still another modification.

Figure 6 is a detail view of the form of eccentric roller shown in Fig. 5.

In the drawings, in the form shown in 40 Figs. 1 and 2, 5 designates a base member of suitable form on which is a housing 6, preferably of a cylindrical sheet metal construction, and having a suitable top 7. Secured to the top, or otherwise suitably mounted 45 in the housing is a driving device, preferably in the form of a spring motor 8, of any desired construction. This motor drives a gearwheel or disk 9 on which is carried a suitable revolving eccentric element, this element in Fig. 2 being shown as a partial cone 10 with its lower edge angularly truncated so that one portion of the cone pre-

jects below the remainder thereof. A winding stem 8^a for the motor may project 55 through the top of the housing.

Below this revolving cone is a cross member 11 having a central disk portion 11^a in the center of which is a conical socket 11^b and on which are diametrically opposed arms 11^c having track or pan supporting 60 terminals 11^d. A pin 12 on the base projects into the central socket 11^b to provide a bearing for the cross member that will permit of a universal rocking motion. The arms 11^c project through openings 6^a in the housing 6.

Secured to the outer end 11^d of the arms is an annular track 13, preferably formed of a dished ring of sheet metal having a plurality of annular ribs 13^a thereon to divide 70 the track member into a concentric series of annular tracks. Suitable gravity propelled objects A may be provided to roll in the tracks.

Upon operation of the motor 8 the eccentric or conical element 10 with its eccentric projection bearing against the cross bar structure 11 of the track, imparts a gyratory or successive rocking motion to the track, whereby the objects A are caused to travel 80 continuously thereabout with the rocking of the track.

In the construction shown in Fig. 3 the arrangement is generally similar to that described in Fig. 2 and corresponding reference numerals designate corresponding parts of the two structures. The only difference is, that instead of using a truncated cone 10 to rock the pan, an eccentric wiper, such as the roller 10^a on an arm 10 secured to wheel 9 is provided. As this roller travels around, it functions to tilt the pan in a gyratory fashion.

Inasmuch as the cone of Fig. 2 has a bearing against the cross support at all 95 points, the tilting motion of the pan is confined and proceeds evenly. To get the same result with the arrangement shown in Fig. 3, it is desirable to provide an annular rib 5^a on the base 5, so that as the roller revolves, the enlarged disk portion 11^a will be depressed against the rib to limit the distance 100 which the cross piece may be depressed.

In the arrangement shown in Figs. 5 and

6, the same principle of operation obtains, but the motor is below the central part of the track. In this arrangement, 15 designates the base plate of a suitable support 5 having cylindrical walls 16. Mounted on the base or otherwise secured within the support, is a driving motor 17, preferably of the conventional spring type, as shown. This motor revolves a wheel 18 on a stationary post 19, and on the wheel is an eccentric element, such as arm 20 with roller 21 for imparting a gyratory rocking motion to the track 22, the central portion only of which is shown, it being of the general construction shown in Figs. 1 and 2.

The post 19 projects through a central point of the track, as shown. The track is maintained in a tilted position by reason of the roller 21 on arm 20, being higher than 20 the rim of the housing 16, the track being supported at diametrically opposite points by the roller and the rim of the housing 16. As the arm 21 revolves, a progressive, tilting motion is thus imparted to the track. 25 A spring 23 on post 19 above the track and held against the track by nut 24 serves to maintain a sufficient pressure on the track to assure satisfactory operation.

A winding stem 25 for the motor may 30 project through the track and serve also as a means to hold the track against rotation.

With any of the above constructions an extremely simple mechanism is provided for imparting the desired motion to the track, 35 and in all of them the motor winding key is conveniently located so that it is accessible from the top of the toy. In all three forms, the revolving eccentric element bearing against a portion of the track structure operates 40 on a cam to tilt the track. While I have illustrated several embodiments of the invention, it will be understood that this is by way of illustration, and that the invention is not confined to the particular constructions shown.

I claim as my invention:

1. In a mechanical toy, a supporting housing, a motor located within the housing, an inclined dished plate member having a track 50 rockably mounted on the supporting housing, revolving means spaced from the center of the plate connected with and driven by the motor and eccentrically contacting with the plate to impart gyratory motion there-

to, and a gravity propelled object on the 55 track.

2. In a mechanical toy, the combination with a fixed supporting housing and a motor therein, of an inclined dished plate member having a series of tracks thereon rockably 60 mounted on the housing, eccentric revolving means connected with and driven by the motor and contacting with the plate member for effecting gyratory motion thereof, and a plurality of gravity propelled objects 65 on the said tracks.

3. In a mechanical toy, a fixed supporting housing, a center post in the housing, a dished plate having a plurality of tracks thereon centrally mounted on the post, a 70 motor in the housing, a cam element driven by the motor in a circle about the post and bearing against a part of the plate for imparting a gyratory motion to the plate, and gravity propelled objects on the tracks of 75 the plate.

4. In a mechanical toy, a supporting housing, a track structure comprising a dished plate associated therewith and having a support on the housing permitting a universal 80 rocking motion, a cam eccentric to the point of support for the track structure and revolvable concentrically about the support for the track structure, in contact with a part of the track structure, a motor operatively 85 connected with the cam, and a gravity propelled object on the track.

5. In a mechanical toy, a motor housing, a motor in the housing, an oscillatory non-rotatable supported plate having a track 90 thereon, a post projecting from the housing engaging the center of the plate, means driven by the motor in a circle about the post and bearing against a part of the plate for imparting a gyratory motion to the plate, 95 and a gravity propelled object on the track.

6. In a mechanical toy, a motor housing, a motor in the housing, an oscillatory non-rotatable supported plate having a track thereon, a post projecting from the housing 100 engaging the center of the plate, means driven by the motor and bearing against a part of the plate for imparting a progressive tilting motion to the plate, and a gravity propelled object on the track.

In testimony whereof I affix my signature,

CHARLES ZABEL.
